UNITED STATES PATENT OFFICE.

GEORGE D. BURTON, OF BOSTON, MASSACHUSETTS, ASSIGNOR TO AMERICAN ELECTRICAL PROCESS COMPANY, A CORPORATION OF MAINE.

WASHING-MACHINE.

No. 857,027.

Specification of Letters Patent.

Patented June 18, 1907.

Application filed November 20, 1905. Serial No. 288,173.

To all whom it may concern:

Be it known that I, GEORGE D. BURTON, a citizen of the United States of America, and a resident of Boston, in the county of Suffolk and State of Massachusetts, have invented certain new and useful Improvements in Washing-Machines, of which the following is a specification.

This invention relates to an apparatus which may be used for various purposes such as washing, degreasing, cleansing, tanning, churning, etc., and consists in providing a tank or vat adapted to contain liquids in which a perforated revoluble receptacle is adapted to rotate, said vat being provided with two electrodes so arranged relative to said revoluble receptacle as to cause the current of electricity passing from one to the other to pass diagonally across said vat through the liquids contained therein.

The invention consists further in providing said revoluble receptacle with one or more perforated partitions.

Of the drawings: Figure 1 represents a perspective view. Fig. 2 represents a cross vertical section taken on line 2—2 on Fig. 3. Fig. 3 represents a horizontal longitudinal section of the principal parts taken on line 3—3 on Fig. 4, and Fig. 4 represents a vertical cross section taken on line 4—4 on Fig. 3.

Similar characters designate like parts throughout the several figures of the drawings.

The apparatus consists of a stationary barrel-shaped tank 7 mounted upon castings or suitable supports 8 and 9. The casting or support 9 serves also as a frame for supporting the propelling gear which consists of a spur gear 10 mounted upon a shaft 11. The spur gear 10 engages with a pinion gear 12 mounted upon a shaft 13 which also acts as a shaft for the direct and reverse pulleys and the loose pulley 14, see Fig. 1.

The automatic reversing device in this construction is arranged to cause the rotating cylinder 17 to turn in one direction from two to eight rotations, more or less, and then reverse automatically and turn from two to eight times, more or less. The stationary tank 7 is made in two sections, the heads 15 and 16 being divided horizontally, (see Fig. 4) one-half of the staves being fastened to the lower sections of the head and the other half of the staves to the upper sections of the

heads, so that the upper half of the tank may be removed to allow of the placing in its position of the rotating cylinder 17, which has journals 18—19 on which it turns. This rotating cylinder has doors 20—21 and corresponding openings for convenience in inserting and removing the fabrics, material, etc., to be treated.

The fixed barrel-shaped tank 7 has a curved sliding door 22 having handles 23. In the drawings the door is represented as open but when the apparatus is in use it should be closed. The rotating cylinder is perforated as indicated at 24—24 and has at intervals projections 25—25 which act as agitators and cause the contents of the cylinder to be thoroughly acted upon by the cleansing fluid, as well as to be equally affected by the electric currents passing from the electrodes 26—27 through the solution and the contents therein.

The electrodes 26—27 may be made of any suitable metal but they are preferably made of aluminium either nickel or silver plated as it has been found by experiment that aluminium thus plated works more advantageously and is more readily cleaned while at the same time it has the least effect upon the materials or substances being treated in this apparatus. These electrodes or plates 26—27 are detachably connected to the heads 15 and 16 by ways or slides 28—29, see Fig. 4, in which the electrodes slide.

Bolts (one of which is shown at 30, Fig. 4) pass through the electrodes and through the heads of the tank and serve the double purpose of fasteners and as electric connectors between the service wires *w w'* and the said electrodes. Narrow openings 31—32, Fig. 1, are made in the upper part of the tank for the insertion and withdrawal when desired of the electrodes 26—27. The end castings 8—9 which support the tank 7 are connected to each other by tie bolts the construction and arrangement of which are shown in Fig. 1. Each complete tie bolt consists of the parts 33—34 of metal and the part 35 of wood, or some other non-conductor of electricity. Set nuts are used to strain up these tie bolts. Bands 37 and 38, see Fig. 1, are used for binding the parts of the stationary tank firmly together and are provided with suitable fastenings such as eye loops 39 and screw bolts 40 which engage with bosses 41.

made on the end of castings 8-9, see Fig. 1. A switch 42 of ordinary construction is used for connecting the service lines W W' with the apparatus.

5 The tank or vat may be filled with any suitable solution the nature of said solution varying with the substance or material to be treated. In any case whatever the solution may be and whatever the use to which the 10 apparatus may be put a direct current of electricity is usually used of from seventy-five to five hundred volts, more or less, and varying in amperage from two to two hundred, more or less, according to the size of the receptacle used and the quantity of material to be 15 treated and the density of the solution. The voltage and amperage will also vary with the density of the solution. This direct current may be obtained from any suitable source. 20 In the use of this apparatus for washing and cleansing it is often desirable that several lots of material may be treated at the same time and owing to a difference in ownership it is desirable that these lots should not be 25 come mixed. To this end the revolving receptacle is provided with a plurality of perforated partitions 43 separating the said receptacle into a plurality of compartments each with an independent door giving access 30 thereto so that when the apparatus is used for certain purposes, such as washing, the articles belonging to one person may be located in one compartment 44 while those belonging to another may be located in 35 another compartment 44^a. This is particularly advantageous when the apparatus is used for cleansing purposes or dyeing. When these partitions 43 are used they are apt to interfere with the current of electricity passing from one electrode to the other 40 when said electrodes are directly opposite each other. In order to overcome this objection and cause a thorough circulation of the current through the perforated revoluble 45 receptacle the electrodes 26-27 are located diagonally opposite each other one at either end of the tank or vat so that the current passing from one to the other will pass diagonally through said receptacle and thoroughly treat the articles in each of the 50 compartments therein.

It is believed that from the foregoing the operation of this invention will be thoroughly understood without any further description.

Having thus described my invention, I claim:

1. The combination of a tank adapted to contain liquids, a perforated revoluble receptacle therein, a perforated partition therein, and two electrodes so located within said tank as to cause a current of electricity to pass diagonally through said liquids.

2. The combination of a tank adapted to

contain liquids, an electrode secured to the 65 front inner face of one of the heads thereof, another electrode secured to the rear inner face of the other head, and a perforated receptacle revoluble in said tank between said electrodes.

3. The combination of a tank adapted to contain liquids, an electrode secured to the front inner face of one of the heads thereof, another electrode secured to the rear inner face of the other head, and a perforated cylindrical receptacle having perforated partitions therein revoluble in said tank between 70 said electrodes.

4. The combination of a tank adapted to contain liquids, an electrode secured to the 80 front inner face of one of the heads thereof, another electrode secured to the rear inner face of the other head, a perforated cylindrical receptacle having perforated partitions therein revoluble in said tank between 85 said electrodes and forming a plurality of compartments, and a closure for each compartment.

5. The combination of a tank adapted to contain liquids, an electrode secured to the 90 front inner face of one of the heads thereof, another electrode secured to the rear inner face of the other head, and a perforated cylindrical receptacle having perforated partitions therein revoluble in said tank between 95 said electrodes, the heads and partitions in said cylinder having a plurality of perforations therein.

6. The combination of a tank adapted to contain liquids, a receptacle mounted upon 100 trunnions and revoluble in said tank, perforated ends to said receptacle, perforated partitions within said receptacle dividing it into compartments, a closure for each compartment, and an electrode within said tank 105 at each end so located that a current of electricity will flow through the liquids in said tank and receptacle diagonally from one to the other.

7. The combination of a tank adapted to 110 contain liquids, a receptacle mounted upon trunnions and revoluble in said tank, perforated ends to said receptacle, perforated partitions within said receptacle dividing it into compartments, a closure for each compartment, a plurality of inwardly extending 115 projections secured to the inner face of each of said compartments, and an electrode within said tank at each end so located that a current of electricity will flow through the liquids in said tank and receptacle diagonally from one to the other.

Signed by me at Boston, Massachusetts, this 18th day of October, 1905.

GEO. D. BURTON.
